UNITED STATES PATENT OFFICE.

LOUIS COURTOT, OF PARIS, FRANCE, ASSIGNOR TO AMERICAN RADIATOR COMPANY,
OF NEW YORK, N. Y., A CORPORATION OF NEW JERSEY.

RADIATOR.

Application filed June 21, 1923, Serial No. 646,893, and in France June 24, 1922.

My invention relates to radiators for hot water or steam heating, of the type in which the radiating surface of each element is constituted by a plurality of tubes, usually vertical, which are connected together at the top and bottom by main chambers whereby all the elements are enabled to communicate.

According to this invention, the walls of the elements are very thin, or below 1 millimetre, as may for example be obtained by an electrolytic deposit upon a core of destructible nature. In order to obtain the requisite strength in spite of this small thickness, the invention consists in giving to the tubes a circular section of small diameter, for instance less than one centimetre, and in connecting said tubes with the main chambers of circular shape. The ends of the tubes are formed as elbows and are joined to said chambers in a substantially perpendicular direction, and in this case the said elements can withstand a considerable internal pressure. Furthermore, in order that said elements may be assembled together by clamping without danger of breakage, the invention also consists in providing strong cross-bracing parts in said main chambers, and after the elements are juxtaposed, said parts will support the necessary pressure which is applied parallel to the axis of the chambers. The width of these latter corresponds as a rule to the diameter of the tubes, and the required spacing of the elements is obtained by the insertion of heavy rings between the corresponding chambers so that the assembling pressure shall be brought to bear upon the whole set of rings and braces which are juxtaposed.

In this manner it will be feasible to construct radiators which for a given heating surface will have a much lighter weight and less size than for the known radiators.

A form of construction of radiator according to this invention is shown in the accompanying drawing by way of example.

Fig. 1 is a front elevation, partly in section.

Fig. 2 is a side elevation, partly in section.

Fig. 3 is a plan view, partly in section.

Figs. 4 and 5 are perspective views of an apertured socket and an inserted ring.

1 indicates a set of tubes of small diameter and thin walls whose ends are bent at an

elbow and are connected in a substantially perpendicular direction to the periphery of two main chambers of circular shape 2. The straight parts of said tubes are situated in a common plane and in parallel disposition. Tubular braces 3 connect together a certain number of the tubes at two or more points on their length, whereby a more rigid construction is afforded.

In this form of construction, each chamber 2 has a width equal to the diameter of the tubes and is traversed by a central metal sleeve 4 of sufficient thickness provided with a plurality of apertures 5 connecting the interior of the sleeve with the annular part of the surrounding chamber. The walls of the latter are assembled in a tight manner with the periphery of the sleeve 4 and are preferably curved outwardly so as to form with the latter a collar of greater or less length 6.

In the preferred form of construction, the said radiator element is obtained by casting in an easily fusible alloy a core having the exact shape of the inner space to be formed in the finished element, and by depositing a layer of copper of suitable thickness upon the whole surface of said core, the latter then being eliminated by melting. By this process which has already been employed for various purposes in the industries, the tubes and the circular chambers are formed in a single piece in a simple and inexpensive manner, and with the maximum tightness and strength.

Before placing the coating upon said core, or even at the time of casting the same, insertion can be made not only of the sockets 4 but also of small copper rods 7 for bracing the chambers 2, thereby providing the most intimate connection between said members and the deposit forming the walls of the element. A number of like juxtaposed elements are preferably assembled by inserting between the same the rings 8 for example of cast iron, steel or the like which are properly fitted upon the ends of the sockets 4 and the collars 6.

These latter are preferably provided on their inner wall with a circular rib 9 which limits the fitting upon the sockets 4. The thickness of the rings 8 in the axial sense corresponds to the desired spacing of the said elements. When the elements are assembled, said rings will bear upon the

braced flat walls of the chambers 2, so that the whole device may withstand strong pressures exerted on the axis of the chambers, as well as the internal pressure.

5 All the elements are placed in communication by the sleeves 4 by means of the apertures 5 of the latter. The number of the said elements will obviously vary according to the desired size of the radiator. The 10 sockets of the elements situated at the end of the series may be screwthreaded or provided with flanges or otherwise disposed for coupling the inlet and outlet piping or suitable plugs, or they may be connected with 15 elements of any other construction and especially with cast iron radiator elements, which will in turn be connected with the piping and can be rigidly connected together so as to form a device wherein the elements 20 with thin walls are not exposed to damage.

Obviously, the said arrangement for assembling the elements which is given by way of example can be varied without departing from the principle of the invention, the same 25 however being considered as the most advantageous.

Claims:

1. A radiator comprising an element consisting of a plurality of tubes of relatively 30 small diameter, and headers formed integrally therewith and having relatively flat body portions each of a width substantially equal to the diameter of said tubes; said tubes and said headers having relatively thin walls of substantially the same thickness providing a homogeneous fluid-tight structure and lying substantially in the same plane with said tubes in separated parallel relation; and the end portions of said tubes converging inwardly to the peripheries of said 35 headers, and arranged substantially perpendicularly thereto, substantially as specified.

2. A radiator comprising an element consisting of a plurality of tubes of small diameter, and relatively flat circular headers formed integrally therewith and lying substantially in the same plane therewith; said 45 element having a relatively thin wall of electrolytically deposited metal to provide a homogeneous fluid-tight structure; and the end portions of said tubes extending angularly inwardly to the peripheries of said headers, and arranged substantially perpendicularly thereto, substantially as specified.

3. A radiator comprising elements having 55 relatively thin walls, and each consisting of a plurality of tubes, and headers therefor having relatively flat body portions, relatively strong sleeves secured centrally within said headers and extending transversely beyond the body portions thereof, rings disposed between the body portions of contiguous elements around said sleeves, and bracing members disposed within said body 60

portions in alinement with said rings, substantially as specified. 65

4. A radiator comprising an element consisting of a plurality of tubes of small diameter, and headers formed integrally therewith; said element having relatively thin walls, and providing a homogeneous fluid-tight structure, and the end portions of said tubes extending angularly inwardly to the peripheries of said headers, and tubular bracing portions formed integrally with said tubes and extending transversely therebetween adjacent to said angular end portions, substantially as specified. 70 75

5. A radiator comprising an element consisting of a plurality of tubes of small diameter having relatively thin walls, and circular headers of relatively large diameter formed integrally with said tubes and lying substantially in the same plane therewith; the intermediate portions of said tubes being arranged in parallelism, and the ends thereof extending angularly inwardly to the peripheries of said headers, substantially as specified. 80 85

6. A radiator comprising an element consisting of a plurality of tubes of small diameter having relatively thin walls, circular headers of relatively large diameter formed integrally with said tubes, and tubular bracing portions extending transversely between 90 95 said tubes, substantially as specified.

7. A radiator comprising elements each composed of a plurality of tubes of small diameter having relatively thin walls, and circular headers of relatively large diameter having body portions each of a width equal to the diameter of said tubes, relatively strong sleeves secured centrally within said headers and extending transversely beyond the said body portions thereof, rings disposed between the body portions of contiguous elements around said sleeves thereof, and bracing members disposed within the body portions of said contiguous elements in alinement with said rings, substantially as 100 105 specified.

8. A radiator comprising elements each composed of a plurality of tubes and circular headers of relatively large diameter formed integrally therewith; said elements having relatively thin walls composed of electrolytically deposited metal, relatively strong sleeves secured centrally within said headers and extending transversely beyond the body portions thereof, rings disposed between the body portions of contiguous elements around said sleeves, and bracing members disposed within the body portions of said contiguous elements in alinement with said rings, substantially as specified. 110 115 120

In testimony, that I claim the foregoing as my invention I have signed my name.

LOUIS COURTOT.
